7 Claims. (Cl. 175—226)

This invention relates to apparatus for collecting samples when samples are gathered from earth strata in geological surveys, and has for its object the provision of means to pull up to the earth's surface samples of optional lengths while maintaining the actual soil strata formation.

In conducting a geological survey each hole is dug to the necessary depth below the surface of the earth, the sample is raised up, and by observations and tests the various physical and dynamic characteristics of earth strata are judged. Therefore it is necessary that the samples supplied for this purpose remain identical to the formation of the ground and also be as long and continuous as possible.

With the presently practiced sample collection methods, although it is possible to obtain long samples, in view of the inability to enfold them in a watertight, airtight manner on the way as they are being pulled up to the earth's surface, they may receive the effects of vacuum phenomena, or under water they may be washed away due to eddy currents. Since accurate observations cannot be made the results of the tests tend to become inaccurate.

The present invention relates to an apparatus for collecting soil samples in which such disadvantages have been eradicated.

For a better understanding of the invention reference is taken to the accompanying drawings, in which,

FIG. 1 is a vertical cross-sectional view of a prior apparatus in which the collected soil sample (hereinafter referred to as "sample") is wrapped with metal foil;

FIGS. 2 and 2a are enlarged cross-sectional views of that part of the same apparatus which cuts-off and retains the sample;

FIGS. 3 and 3a are vertical cross-sectional views of a part of the apparatus of the present invention;

FIGS. 4 and 4a are horizontal cross-sectional views of the sample cutting-off part;

FIGS. 5 and 5a are vertical cross-sectional views of a second embodiment of the present invention;

FIGS. 6 and 6a are vertical cross-sectional views of a third embodiment of the present invention;

FIGS. 7 and 7a are cross-sectional views along A—A;

FIGS. 8 and 8a are vertical cross-sectional views of a fourth embodiment of the present invention;

FIGS. 9 and 9a are vertical cross-sectional views of a fifth embodiment of the present invention and

FIGS. 10 and 10a are vertical cross-sectional views of a sixth embodiment of the present invention.

In past collection of samples, such as for example with the apparatus depicted in FIG. 1, rotor 2 is caused to rotate about sampler 1, pressurized water is supplied into the space between 1 and 2, and as the hole is drilled by bit 4, the sample is caused to progressively enter into interior 5 of sampler 1 and the sample is wrapped by a narrow long metal foil 6. At the same time as shown in FIGS. 2 and 2a, due to a spring contrivance such as coil spring 7, steel band 8 is caused to advance toward the center of the cross-section of the sample, thus cutting it off. Also a method is employed to support that end and pull it up to the earth's surface, but according to this method the sample is not wrapped up in a water-

2

tight or airtight manner and will be disturbed due to water and air. Also the end portion cannot avoid being washed out by disturbances such as vacuum and eddy currents.

5 The above facts are detailed in the following publication: Royal Swedish Geotechnical Institute Proceedings, No. 1, "Soil Sampler with Metal Foils," W. Kjellman, T. Kallstenius and O. Wager, Stockholm, 1950.

In the first embodiment of the present invention as depicted in FIGS. 3 and 3a, there is shown two main parts inner cylinder 9 and outer cylinder 10. Inner cylinder 9 is divided into head part 9a possessing a thin cutting edge, and main part 9b. The joint of these two parts is comprised of conical frustum surfaces fitting into each other and, since they may be fitted in coaxially, they can readily be separated from each other. At the lower part of inner cylinder 9b and next to the joint is attached sample cutter 11, and immediately above it is the double walled cylinder for the purpose of forming the loading chamber 12 for the sample wrapping bag. At the upper end of loading chamber 12 is extension outlet 13 for the wrapping bag, facing toward the inside of inner cylinder 9b. The inside diameter of inner cylinder 9b is slightly larger from above the extension outlet 13.

10 Into loading chamber 12 cylindrical wrapping bag 14 is pushed, with the end of the bag closed by tying so that the entire lateral cross-section of inner cylinder 9b will be wrapped and sealed off. On the outer part of the head part 9a of the inner cylinder is located flange 15.

15 Overlapping inner cylinder 9 is outer cylinder 10 which can freely rotate about the inner cylinder and which is equipped at its extremity with bit 4 for drilling, and located near this and facing inward is a flange for attaching bearing 16.

20 30 The head part of the inner cylinder near the joint increases in diameter so that, although outer cylinder 10 overlaps it with freely slidable rotation, the two parts cannot be mutually removed, and even when ball bearing 16 of the outer cylinder contacts outer flange 15, the cutting edge of the head part of the inner cylinder will always protrude beyond outer cylinder 10.

25 35 Near ball bearing 16, on the inner surface of outer cylinder 10, are four protrusions 17 facing inward. When outer cylinder 10 slidably moves so that the protrusions 40 45 17 are caused to engage with the indented and protruding part 11' on the outside of the rotating ring meshed with the cut-off blades attached to main part 9b of the inner cylinder, and the rotating ring of cutter 11 is rotated in the clockwise direction, as shown in FIGS. 4 and 4a the sixteen cut-off blades in four rows of the cutter move toward the center of the inner cylinder, cut off the sample, and moreover by means of the sixteen cut-off blades seal it within the inner cylinder.

40 45 50 Next the action of the apparatus of the present invention will be explained.

55 In the first embodiment of the invention outer cylinder 10 overlaps inner cylinder 9, and while supplying pressurized water into the space between inner cylinder 9 and outer cylinder 10 and while pushing on outer cylinder 60 65 70 75 80 85 90 95 100 105 110 115 120 125 130 135 140 145 150 155 160 165 170 175 180 185 190 195 198 200 205 210 215 220 225 230 235 240 245 250 255 260 265 270 275 tremity, which is shaped like an inverted U, of the wrapping bag 14 which slides out from the upper portion of wrapping bag loading chamber 12 that is attached to the lower extremity of main part 9b of the inner cylinder. Moreover, accompanying entrance of the sample, its top and sides are covered accordingly by the bag and in this manner advances into the interior of main part 9b of the inner cylinder. By filling the space between the bag and main part 9b of the inner cylinder with liquid of lubricating characteristics such as soap solution, caustic soda solution or some type of oil, friction is decreased together with prevention of injury to the sample due to shock.

To raise the sample up to the surface of the earth, the supply of water is stopped, rotation of outer cylinder 10 is stopped, and if outer cylinder 10 is moved until sloped surface 19 near the extremity of outer cylinder 10 touches slope surface 20 on the outside of head part 9a of the inner cylinder, projections 17 on the inside surface of outer cylinder 10 will engage teeth 11' which have been cut into the outer surface of the lower end of the inner cylinder. At this point if outer cylinder 10 is gradually rotated in the clockwise direction, movable part 11 provided on inner cylinder 9 will rotate in unison. At this time, gear 21 on inner face of movable part 11 rotates gear 22 which is integral with cut-off blades 18 attached in four rows to the inner face of movable part 11, and cut-off blades 18 will bite into the sample, moving toward the center of inner cylinder 9, and will cut-off the sample. When the tips of the cut-off blades reaches the center of the cross-sectional plane of the inner cylinder, the extremities of cut-off blades 18 will abut against each other and outer cylinder 10 cannot be rotated further. Thus, the sixteen cut-off blades 18 which are provided in four rows will completely sever the sample and seal off the cut-off face.

At this point if main part 9b of the inner cylinder is pulled up to the earth's surface, the sample is wrapped around it and at the upper end by the bag, while the lower end is sealed by cut-off blades 18, and the sample can be collected in this state.

Next the details of the second embodiment of the present invention will be explained in conjunction with the drawing. As depicted in FIGS. 5 and 5a, in the second embodiment of the present invention, inner cylinder 9, head part 9a, which possesses a thin cutting edge, and main part 9b are connected together by an abutting sawtooth joint and can be separated. Also sample cutters 11 are provided on internal cylinders 9b and 9a respectively. In other respects, it is identical to the first embodiment.

In the second embodiment of the present invention, if protruding parts of outer cylinder 10 and the indented and protruding part of the outer rotating ring of cutter 11 are caused to engage with each other and then rotated in the clockwise direction, the top and bottom two rows of cutters 11b and 11a will simultaneously cut-off the sample, and at the same time seal it just the same as in the first embodiment. Thus, while cutting off with upper and lower two rows of cut-off blades, when main part 9b of the inner cylinder is pulled out from outer cylinder 10, the sample will be wrapped in wrapping bag 14, with its lower portion protected by cut-off blades 18, and the sample can be collected in an undisturbed condition.

Also after main part 9b of the inner cylinder has been removed, head part 9b of the inner cylinder remains in the earth, and since cut-off blades 18a of cutter 11a are hermetically closed, water or soil is prevented from invading into inner cylinder 9a.

After the sample in the main part 9b of the inner cylinder has been taken out as above mentioned, wrapping bag 14 is packed into loading chamber 12 and the end is sealed off in an inverted U shape with cut-off blades 18b in hermetically closed position, and main part 9b of the inner cylinder is inserted into outer cylinder 10, and,

while quietly rotating in the clockwise direction, the parts interconnecting main part 9b and head part 9a of the inner cylinder are made to completely mesh together by means of the sawtooth joint.

Subsequently if inner cylinder 9 is rotated in the counterclockwise direction, the upper and lower cut-off blades will simultaneously open up. Next the sending of water is commenced, outer cylinder 10 is pushed down, rotated, and collection of the next sample is conducted.

As aforementioned, in the first and second embodiments of the present invention, if the necessary length of wrapping bag 14 is loaded into the loading chamber 12, the above procedure can be continued and, no matter how long the sample, it can be collected in continuous form and, moreover, in an undisturbed state. Also cut-off blades 18 will mutually contact each other to hermetically seal the sample within the inner cylinder and, because it will be cut-off from the exterior, there will be no fear that the sample, while being pulled up, will suffer disturbance or loss by washing out due to effects of vacuum phenomena or eddy currents during water immersion, and it is possible to collect perfect samples of earth strata, thus enabling conduction of effective geological surveys.

In the third embodiment of the present invention as depicted in FIGS. 6 and 6a, the inner surface of cylinder 9 has valve 25 with blades having thin cutting edge tips and which are supported and free to rotate in a range from a position parallel to the cylinder wall to a direction at right angles to it, about sealing valve shaft (hereinafter referred to as "shaft") 24, with chamber 12 constituting an integral part. The extension outlet for bag 14 is located at the vicinity where the valve tips contact the inner wall of the cylinder.

In order to collect a sample, bag 14 is compressed and packed into chamber 12 and its end is sealed off. The head part of cylinder 9 is held vertically in the ground or at the surface of the earth, and when the cylinder 9 is driven into the ground by striking its head with a hammer, the sample will progressively enter into cylinder 9. In this instance, if the valve is sealed cylinder 9, the sample will automatically push the valve blades against the inner wall of the cylinder, and as in FIG. 6a, will advance into the cylinder.

When the sample reaches the sealed off end of bag 14, the bag will automatically, at the same speed as the entrance of soil and sand, extend out from chamber 12 and enfold the sample.

By continuing the above-mentioned operation the samples of earth strata formation will all be of cylindrical rod form and successively stored in cylinder 9 as wrapped in bag 14.

In this manner, when driving in to the specified depth has ended, cylinder 9 is pulled up to the earth's surface.

When cylinder 9 is started to be pulled up, the sample within cylinder 9, by its own weight, will tend to drop outside from the lower end of cylinder 9 but as soon as even a small part of the sample shows a tendency to drop outside, valve 25 which has been pushed against the inner wall of cylinder 9 will, due to friction with the sample, rotate so as to lean toward the center of cylinder 9 and prevent sliding out of the sample. Despite this if sliding out of the sample does not cease, although soil and sand below the portion supported by valve 25 will drop toward the exterior of cylinder 9, valve 25, while holding the sample, will rotate and finally reach the position where it will be at right angles to the central axis of cylinder 9, and as in FIG. 6, will close off the interior of cylinder 9 and completely prevent dropping out of the sample.

In the fourth embodiment of the present invention, as depicted in FIGS. 8 and 8a, cylinders 9b and 9a are coupled in a slidingly rotatable manner but will not come apart. At the lower extremity of cylinder 9b is chamber 12 and at its lower end is the extension outlet for bag

14. From above chamber 12 the cylinder is single walled. Also the extremity of cylinder 9a is a thin cutting edge while the upper portion is a part doubly coupled to cylinder 9b with valve 25 in the inner face provided to make possible, by rotation about shaft 24, the closing off of cylinder 9a.

On the inner face of cylinder 9b, at the part opposite to shaft 24, is notch 26 and also at its extremity is internal flange 27.

At the upper end of cylinder 9a is attached shaft 24 and, to engage with flange 27 on the inner face of cylinder 9b, is notch 28.

Valve 25 is hinged to shaft 24 and on the rear face of the shaft part of valve 25 is a protruding part which will engage with the notch in cylinder 9b.

In order to collect the sample, bag 14 is compressed and packed into chamber 12, and its end is sealed off.

With cylinder 9a on the bottom and cylinder 9b at the top they are mutually connected together, and when placed vertically at the earth's surface or in the ground, the lower extremity of cylinder 9b closely contacts the upper face of the externally notched part of cylinder 9a, and simultaneously the protruding part on the rear face of the shaft part of valve 25 will be pushed downward by the notched portion 26 of cylinder 9b. Accordingly valve 25 is pushed against the inner face of cylinder 9b and, as in FIG. 8a, the interior of cylinder 9a will be opened. At this point if the head of cylinder 9b is struck to drive it into the ground, the sample enters from cylinder 9a into cylinder 9b, reaches the sealed off portion of bag 14 and enters into cylinder 9b. In this manner, when driving in to the specified depth has ended, cylinders 9b and 9a are pulled up to the earth's surface.

After commencing to pull up cylinder 9b, at about the same time its internal flange 27 contacts the lower face 28 of the external flange of cylinder 9a, the lower face of notch 26 on cylinder 9b will push up against the lower face of the protruding part on the rear face of the shaft part of valve 25, and due to lever action valve 25 departs from the inner wall of cylinder 9b and leans in a direction at right angles toward the center of cylinder 9b, and as in FIG. 8, will seal off the interior of cylinder 9b, thus preventing dropping out of the sample from cylinder 9b and enabling its perfect collection.

In the fifth embodiment of the present invention, as depicted in FIGS. 9 and 9a, cylinders 9b and 9a, which are mutually freely slidably rotatable, are doubly connected, and form an integral body. In this embodiment, differently from the fourth embodiment, valve shaft 24 is attached to cylinder 9b and valve 25 is caused to be closed by pushing up with the extremity of cylinder 9a.

Now if cylinders 9b and 9a are joined together by overlapping as in FIG. 9a, valve 25 is pushed against the inner wall of cylinder 9b by the tapered portion of cylinder 9a and the interior of cylinder 9b is open. In this condition, if the driving in work is continued, the same as with the other embodiments, the samples will all be of round rod shape, and as wrapped by bag 14 will successively be stored within cylinder 9b.

When driven in to the specified depth, if cylinder 9 is pulled up, the internal flange 27 at its extremity will slide against the outer surface of cylinder 9a and reach external flange 28 of cylinder 9a. At the same time, the tapered portion of cylinder 9a which had been pushing valve 25 against the inside wall of cylinder 9b slides past below the front face of valve 25, and valve 25 will commence to lean toward the center of cylinder 9b and finally as in the left hand side of FIG. 9, closes off cylinder 9b and completely prevents dropping out of the sample.

The sixth embodiment of the present invention is an instance where the present invention is employed in the rotary type and, as depicted in FIGS. 10 and 10a while

delivering pressurized water 3 through the space between soil sample collecting cylinder 10 and drilling cylinder 9, drilling cylinder 9 is caused to rotate in the clockwise direction. Pressurized water 3 passes through water spray holes 29, spouts out in the vicinity of drilling bits 4, softening earth strata and making drilling progress easy, and return flows to the earth's surface together with waste soil and sand.

In this manner, as drilling progresses, the sample successively enters into cylinder 9, and is automatically wrapped by the bag at the extension outlet of the chamber, and is stored within the cylinder.

When drilling has progressed to the specified depth, when the cylinder is pulled up, external flange 27 at the lower extremity of the cylinder automatically engages the protruding part on the front face of the shaft part of valve 25 provided at the inner face of outer cylinder 10, and since it will be pulled up in this manner, valve 25 will seal off outer cylinder 10.

Since in this manner the cylinder is pulled up to the earth's surface, not only can the sample be perfectly collected, but simultaneously with the pulling up of the sample, the bottom of the drilled hole is automatically sealed up and it is possible to prevent collapse of the interior of the hole due to spouting out of soil, sand or muddy water.

What I claim is:

1. An apparatus for collecting soil samples comprising a cylinder having an outer portion, and an inner portion mounted for limited slidable movement within said outer portion; soil cutting means located at one end of said inner portion and extending outwardly from the adjacent end of said outer portion; a wrapping bag loading chamber disposed on the inner wall of said cylinder and spaced from said end; a wrapping bag partially disposed in said chamber and extending across said cylinder in a plane perpendicular to the longitudinal axis thereof; a plurality of drill bits disposed on said adjacent end of said outer portion; and means disposed on said cylinder to seal said soil sample from the soil after the sample has entered said cylinder upon insertion of said cylinder into the soil, said sealing means comprising a ring rotatably mounted on said inner portion, a plurality of cutting blades pivotally mounted on said ring normally extending around the inner wall thereof, and adapted to be pivoted about one end in a plane perpendicular to the longitudinal axis of said cylinder to cut said sample and seal it from the soil upon rotation of said ring, and means to actuate said sealing means.

2. The apparatus of claim 1 wherein said actuating means comprises a plurality of protrusions extending from the inner wall of said outer portion and adapted to engage said ring to transmit rotation of said outer portion to said ring.

3. An apparatus for collecting soil samples comprising a cylinder having an outer portion, and an inner portion mounted for limited slidable movement within said outer portion, said inner portion comprising an upper portion on which said chamber is disposed, and a lower portion, adjacent ends of said upper portion and said lower portions forming a sawtooth joint to quickly detachably connect said portions; soil cutting means located on said lower portion and extending outwardly from the adjacent end of said outer portion; a wrapping bag loading chamber disposed on the inner wall of said cylinder and spaced from said end; a wrapping bag partially disposed in said chamber and extending across said cylinder in a plane perpendicular to the longitudinal axis thereof; a plurality of drill bits disposed on said adjacent end of said outer portion; and means disposed on said cylinder to seal said soil sample from the soil after the sample has entered said cylinder upon insertion of said cylinder into the soil.

4. An apparatus for collecting soil samples comprising

ing a cylinder; soil cutting means located at one end of said cylinder; a wrapping bag loading chamber disposed on the inner wall of said cylinder and spaced from said end; a wrapping bag partially disposed in said chamber and extending across said cylinder in a plane perpendicular to the longitudinal axis thereof; and means disposed on said cylinder to seal said soil sample from the soil after the sample has entered said cylinder upon insertion of said cylinder into the soil, said sealing means comprising a plurality of blades pivotally mounted on said cylinder and adapted to be moved from a normal position parallel to said cylinder wall to a cutting and sealing position perpendicular to said cylinder wall, the movement of the sample upward into said cylinder retaining said blades in their normal position and the movement of said cylinder upward from the soil, causing the sample to engage said blades to cut the sample and seal it from the soil.

5. An apparatus for collecting soil samples comprising a cylinder having an outer portion, and an inner portion mounted for limited slidable movement within said outer portion; soil cutting means located at one end of said inner portion and extending outwardly from the adjacent end of said outer portion; a wrapping bag loading chamber disposed on the inner wall of said cylinder and spaced from said end; a wrapping bag partially disposed in said chamber and extending across said cylinder in a plane perpendicular to the longitudinal axis thereof; and means disposed on said cylinder to seal said soil sample from the soil after the sample has entered said cylinder upon insertion of said cylinder into the soil, said sealing means comprising a plurality of cutting blades pivotally mounted on said inner portion and adapted to be pivoted from a normal position parallel to said cylinder wall to a cutting and sealing position perpendicular to said cylinder wall, and means on said outer portion adapted to engage and move said blades upon relative movement between said inner and outer portions.

6. An apparatus for collecting soil samples comprising a cylinder having an outer portion, and an inner portion mounted for limited slidable movement within said outer portion; soil cutting means located at one end of said inner portion and extending outwardly from the adjacent end of said outer portion; a wrapping bag loading chamber disposed on the inner wall of said cylinder and spaced from said end; a wrapping bag partially disposed in said chamber and extending across said cylinder in a plane

perpendicular to the longitudinal axis thereof; and means disposed on said cylinder to seal said soil sample from the soil after the sample has entered said cylinder upon insertion of said cylinder into the soil, said sealing means comprising a plurality of cutting blades pivotally mounted on said outer portion and adapted to be pivoted from a normal position parallel to said cylinder wall to a cutting and sealing position perpendicular to said cylinder wall, the outer end of said inner portion normally retaining said blades in their normal position and releasing said blades upon relative movement between said inner and outer portions.

7. An apparatus for collecting soil samples comprising a cylinder having an outer portion, and an inner portion mounted for limited slidable movement within said outer portion; a soil cutting means located at one end of said inner portion and extending outwardly from the adjacent end of said outer portion; a wrapping bag loading chamber disposed on the inner wall of said cylinder and spaced from said end; a wrapping bag partially disposed in said chamber and extending across said cylinder in a plane perpendicular to the longitudinal axis thereof; and means disposed on said cylinder to seal said soil sample from the soil after the sample has entered said cylinder upon insertion of said cylinder into the soil, said sealing means comprising a plurality of cutting blades pivotally mounted on said outer portion and adapted to be pivoted from a normal position parallel to said cylinder wall to a cutting and sealing position perpendicular to said cylinder wall, a first projection extending from one end of each of said blade members, a projection extending from the outer wall of said inner portion adapted to engage said first projection to move said blades to their cutting and sealing position upon relative movement between said inner and outer portions.
